UNITED STATES PATENT OFFICE

WILLIAM J. STEBLER, OF PITTSBURGH, PENNSYLVANIA, ASSIGNOR OF ONE-EIGHTH TO M. A. HERALD, ONE-EIGHTH TO ROBERT ROGERS, ONE-FOURTH TO D. J. McLAUGHLIN, AND ONE-FOURTH TO WALTER J. CURLEY, ALL OF PITTSBURGH, PENNSYLVANIA

SAFETY GUARD DEVICE

Application filed December 30, 1927. Serial No. 243,583.

This invention relates to safety hangers for brake-lever connecting-rods for railway cars.

The objects of the invention are to provide a simple, effective, easily attached and detached safety catch of the class referred to; to provide this guard with attaching means adapted to cooperate with brake-beam safety catches, whereby to render the attaching means of both such safety supports more simple and more secure.

Other objects and advantages will be apparent to those familiar with such structures from a reading of the following specification and an inspection of the drawing.

Referring to the drawings, Fig. 1 is a side elevation of a spring plank with brake-beam supports and the present safety hanger attached to the spring plank; Fig. 2 is a vertical cross section through the spring plank on the line II—II; and Fig. 3 is a perspective view from a point below the spring plank, showing the brake-beam supports and the connecting rod safety hanger loop as attached to the spring plank.

In my copending application Serial No. 207,629, filed July 22, 1927, I have described a brake-beam support or safety catch comprising arms extending laterally from the spring plank, and attached to the spring plank by a pair of hook members extending over the flanges thereof, the two arms of the support being connected together under the middle of the spring plank by a compression bolt. In order to positively engage the square head of the bolt one of the safety catch members has to be turned downward and then outward to form an abutment for the non-circular head of the bolt. This requires an additional operation in the manufacture of that part of the device, renders the two main parts of the device non-symmetrical, and requires a compression bolt for attaching the two parts together. A compression bolt is required rather than a rivet because resilient reaction

of the parts is required in order to secure a sufficient frictional grip upon the spring plank to prevent displacement of the catches longitudinally of the spring plank.

The device referred to in the previous application concerns only safety guards for

brake-beams. The present device adds a safety guard for the brake-actuating connecting rod.

As will be readily understood by those familiar with the art, brakes are applied by levers which have an operative connection running under the trucks to an air cylinder. Sometimes these connections become loose, due to the coming out of a pin or the like. In that case the end of the connecting rod may fall upon the track, and if the loose end is in the direction of travel of the car, the connecting rod may be driven through the floor of the car, or it may lift the truck and derail the car. For this arrangement it is highly desirable to provide means approximately at the middle part of the connecting rod to catch and support it in case either end becomes loose.

The present invention combines with the brake beam safety supports or catches referred to in my previous application a connecting rod safety catch in the form of an enclosing loop. The two cooperate in that the supporting member for the connecting rod loop acts as a spacer for the brake beam supports, permitting simplification of construction in the latter, and rendering their positioning and functioning more certain.

Referring to the drawing, a standard spring plank P is illustrated. The positioning of such a member in a car truck is well understood, and will not be described in detail. These members are ordinarily positioned with the flanges F turned up, as illustrated in Fig. 1. Near each end of the spring plank there are secured brake-beam safety catches or supports comprising a pair of hook members H, having terminal inward and downward portions 1, adapted to extend over the edges of the flanges F of the spring plank, as illustrated in Fig. 1. These hook members are extended at their lower end outward to form the arms for catching a loose brake-beam, or else are riveted, welded or otherwise attached to separate members forming such arms. As illustrated in the present drawing the hook members H have a downwardly extending portion 2 lying against the outer face of the spring plank flange, and a hori-

zontal portion 3, which is rigidly attached to a horizontal arm member 4 by means of rivets R. This arm member 4 extends inward to the middle portion of the spring plank and then has a downwardly bent vertical portion 6, which is perforated at about its middle portion to receive a rivet or bolt 7. A similar structure is adapted to be oppositely positioned on the other flange of the spring plank. The two portions 6 are thus brought close together but not in contact along the middle longitudinal portion of the spring plank, as illustrated in Fig. 2. When the two adjacent portions 6 are fastened together, as by the rivet 7, the brake-beam support is complete.

To this structure, in the present case, there is added a carrier bar 10, which extends on the under side of the spring plank along its middle line. Towards the outer ends of this bar there are U-shaped cuts or notches 11 on the same side of the bar, extending inward from the under edge thereof when the bar is in normal position as shown in the drawings. At the middle portion of the bar 10 a depending bracket or loop 12 is provided. The ends of the loop are attached to the bar 10 by means of rivets 13. The loop 12 is deep enough and broad enough to extend around the usual connecting rod 14 of the brake-actuating mechanism. This connecting rod may extend to a lever as illustrated, or other member operatively connected to the air cylinders. In case either end of this connecting rod becomes loosened, the loop 12 will act as a safety catch, supporting the rod until it can be reconnected at the loose end.

The cuts 11 in the bar 10 are positioned at the points where the brake-beam safety supports are to be placed upon the spring plank. The bar extends between the two portions 6, 6, of the brake-beam guard assembly as shown in Fig. 2, and the rivet 7 which connects these two portions 6, 6 extends through the opening 11 in the bar 10. The outer ends of this bar abut against fixed truck members 15, which prevent any lateral displacement of the bar, and consequently prevent any displacement of the brake-beam safety supports upon the spring plank.

The present structure permits the use of a rivet 7 for connecting the two arms of the brake-beam supports, instead of a compression bolt. This is because the brake-beam supports are positively positioned and retained in position by means of the bar 10 through which the rivets 7 extend at fixed points. Consequently there is no need for a compression bolt or other adjustable device for connecting the two halves of the brake beam supports, since no reliance need be placed upon the frictional grip of the supports on the spring plank, the supports being slidable on the spring plank except for the positive spacing of bar 10. This does away with an additional operation for forming an

abutment for a bolt head, as was previously required for such brake-beam support assemblies, and permits making the pairs of members for the brake-beam supports identical and therefore interchangeable. Since the rivet 7 is positioned entirely beneath the spring plank it is easy for workmen to put it in or take it out at this point on a car on a track. No holes or other changes are required in the spring plank and no fixed members whatever have to be added to the truck structure in order to provide this safety loop and to positively position the brake-beam catches. At the same time a riveted-up substantially rigid safety guard assembly both for brake-beams and brake-lever connecting rods is provided.

I claim:

1. In a railroad car truck, a safety loop for a brake-operating connecting rod, a bar carrying said loop, said bar being adapted to extend longitudinally on the under side of the spring plank of the car truck and to abut fixed parts of the car truck at each end, and means to attach the bar to the spring plank near the ends of the bar.

2. In a railroad car truck, the combination of brake-beam safety catches, a safety loop for the brake-operating connection, a bar carrying the loop, said bar abutting fixed parts of the truck at each end and also positively engaging the brake beam catches and spacing them apart.

3. In a railroad car truck, the combination of a spring plank, brake-beam safety catches supported under and by the spring plank, a bar longitudinally positioned under the spring plank and abutting fixed parts of the truck at each end, a safety loop carried by said bar and adapted to enclose a brake-actuating connecting rod, and members extending through said bar and said brake beam catches whereby to position the catches relative to the bar and to prevent movement thereof longitudinally of the spring plank.

4. In a railroad car truck comprising a spring plank and brake mechanism, the combination of safety supports for brake-beams and a safety support for connecting rods, comprising brake-beam supports composed of pairs of oppositely positioned similar members adapted to hook over upturned flanges of a spring plank and to be connected through down-turned perforated spaced apart terminals positioned beneath and near the middle longitudinal line of the spring plank, a bar positioned beneath the spring plank extending longitudinally thereof and abutting fixed parts of the truck at each end, a loop adapted to surround a brake-actuating connecting rod and to serve as a safety catch therefor, said bar having openings therethrough and being positioned between the above referred to members of the brake-beam supports, and connections extending through

said openings in said bar and fastening together said terminals of the brake-beam support members of each pair.

5. In a railroad car truck construction comprising a spring plank with up-turned flanges and a brake mechanism, safety supports for brake beams comprising arm members adapted to extend on each side of the spring plank under brake-beams of the truck and having hooks for engaging the flanges of 10 the spring plank, said arm members extending under the spring plank and having their ends turned down to form spaced-apart parallel perforated terminal portions, a bar extending longitudinally of and under the spring plank and between said spaced-apart 15 terminals of the arm members, and fastening members connecting said terminal members through said bar, whereby to connect and positively position the safety support 20 arms on the spring plank.

In testimony whereof, I sign my name.

WILLIAM J. STEBLER.
